Primary Examiner — Jennifer Rivard(74) *Attorney, Agent, or Firm* — Workman Nydegger(57) **CLAIM**

An ornamental design for multiple nail design label sheet, as shown and described.

DESCRIPTION

FIG. 1 is a perspective view of our design;

FIG. 2 is a front view thereof, the rear view being unornamented;

FIG. 3 is left side view thereof;

FIG. 4 is a right side view thereof;

FIG. 5 is a bottom plan view thereof; and,

FIG. 6 is a top plan view thereof.

The broken lines illustrate portions of the article and form no part of the claimed design.
